UNITED STATES PATENT OFFICE.

JOHN C. ROBERTS, OF HARRISBURG, TEXAS.

VALVE LIFTER.

Application filed June 1, 1926. Serial No. 112,828.

This invention relates to new and useful improvements in a valve lifter.

One object of the invention is to provide a lifter of the character described specially designed to be used in internal combustion motors and through which the valves of the motor may be actuated, or elevated practically noiselessly.

Another object of the invention is to provide a two part valve lifter having a resilient cushion interposed between them which will provide the proper clearance for expansion under heat and enable the respective ends of the lifter to ride against the actuating cam at one end and the valve stem at the other, thus avoiding the usual tapping noise incident to the usual valve operation of internal combustion motors.

With the above and other objects in view the invention has particular relation to certain novel features of construction, operation and arrangement of parts, an example of which is given in this specification and illustrated in the accompanying drawings, wherein:-

Figure 1 shows a fragmentary vertical sectional view of an internal combustion motor showing the valve and valve lifter mounted therein, and

Figure 2 shows a side elevation of the valve lifter.

Referring now more particularly to the drawings, wherein like numerals designate similar parts in each of the figures the numeral 1 designates a motor having cylinders, as 2, each provided with a valve seat as 3, which is controlled by the inwardly opening valve, as 4. Fastened to the valve there is a stem 5 which works through the bearing 6 and which has fixed thereon a collar 7, interposed between which, and the bearing, 6 there is a pressure spring 8 which surrounds said stem and which normally holds the valve 4 closed.

The numeral 9 designates the valve lifter, as a whole, which is aligned with the stem 5 and works through the bearing 10. The numeral 11 designates the cam shaft having the cam 12 fixed thereon, which rides against one end of the valve lifter and actuates said lifter, the other end of the lifter operating against the end of the valve stem 5.

As now constructed and used the valve

lifter is rigid and there must be a clearance left between the stem 5 and the adjacent end of the lifter to allow for the expansion of the parts when they become hot. Without this clearance when the valve stem 5 becomes hot and expands the valve would be held open. This clearance causes the lifter to strike the opposing end of the valve 5 as the lifter is actuated causing an objectionable tapping or noise which it is sought to overcome. In order to accomplish the desired result I have formed the lifter of two main parts 13 and 14, the latter telescoping within the former, and being seated on a coil spring 15 interposed between them. The inner end of the part 14 is enlarged forming an external annular shoulder 16 thereon and a gland 17 is screwed into the part 13 with its inner end opposing said shoulder and this gland may be adjusted to limit the range of movement of the part 14 and is held in said adjusted position by means of the lock nut 18. The outer end of the part 14 is protected by the cap 19 which is screwed thereon and which takes the wear, and this cap is locked in position by means of the lock nut 20.

In operation the cam 12 operates against the adjacent end of the part 13 which is held yieldingly thereagainst by the spring 15 and operates to compress said spring and thereafter to also actuate the part 14 against the valve stem to lift said valve. Inasmuch as the cap 19 is in constant contact with the opposing end of the valve stem 5 this operation will be practically noiseless.

What I claim is:-

1. A valve lifter including two relatively movable parts, a yieldable member interposed between said parts, one end of the lifter being formed with an enlarged head, a detachable wearing cap carried by the other end of the lifter and an adjustable gland carried by the head.

2. A valve lifter including a female member, a male member adapted to move longitudinally relative thereto, a spring cushion upon which the male member rests, a gland screwed into said female member and limiting the movement of the male member and a cap upon the free end of the male member.

3. A valve lifter including a female member, a male member telescoping within said

female member, a yieldabl seat within the female member on which the male member is seated, the outer end of the male member being reduced forming an annular shoulder, 5 a gland surrounding said male member and threaded into the female member and whose inner end opposes said shoulder, a lock nut threaded on to said gland and abutting the adjacent end of said female member and a detachable cap carried by the outer end of the male member.

In testimony whereof I have signed my name to this specification.

JOHN C. ROBERTS.
